MINERAL WATER SIPHON BOTTLE

Edward Joseph Paul Eugster, London, England

Application April 5, 1935, Serial No. 14,944
In Great Britain April 11, 1934

6 Claims. (Cl. 215—5)

This invention relates to mineral water siphon bottles and similar containers for storing and dispensing aerated liquids under pressure, and has for its object to provide a new and improved means for effecting the discharge of the contents of containers of the kind referred to so that the aerated liquid can be dispensed with a minimum loss of aeration.

According to the present invention a siphon bottle or similar container of the kind referred to is provided with means to permit the escape of excess gas collected above the level of the aerated liquid in advance of the delivery of such liquid through the discharge head when the valve therein is operated, so as to reduce the internal gas pressure sufficiently to effect a quiet and relatively unbroken delivery of the aerated liquid.

In a convenient manner of carrying out the invention, a non-return gas release valve is arranged in the carrier by which the siphon tube is suspended in the container, or in the upper part of the siphon tube when the carrier is dispensed with, so as to normally close one or more apertures formed in such carrier or tube in order to interconnect the gas space above the level of the liquid stored in the container, with the valve in the discharge head.

The non-return release valve is automatically opened by unbalanced pressure of the gas trapped in the container as the valve in the discharge head is operated, so that excess gas escapes past the release valve through the valve in the discharge head in advance of the aerated liquid rising through the siphon tube.

To facilitate the escape or shift of gas in advance of the delivery of aerated liquid through the discharge head a non-return liquid release valve is arranged in the siphon tube or its carrier, as the case may be, below the gas vent aperture or apertures therein so as to close the upper end of the siphon tube and prevent the aerated liquid rising therethrough until the liquid release valve is opened by the progressive operation of the valve in the discharge head.

The invention is further described with reference to the accompanying drawing, wherein similar references indicate corresponding parts.

Fig. 1 is a fragmental vertical sectional view of a mineral water siphon bottle illustrating one embodiment of the invention adapted for use with a discharge or siphon head of short lever pattern. Fig. 2 is a detail view further illustrating a spring for controlling the non-return gas relief valve shown in Fig. 1. Figs. 3 and 4 are respectively vertical sectional views illustrat-

ing other embodiments of the invention for use with mineral water or like bottles or containers furnished with discharge heads of the short lever pattern, and Fig. 5 a cross section view on the line V—V Fig. 4.

As shown in the drawing, the siphon tube 1 is suspended in the bottle 2 by means of a carrier 3 in which one or more apertures 4 is or are formed, which aperture or apertures is or are normally closed by a non-return gas release valve 5 mounted in the carrier for this purpose, so that when the carrier 3 and its siphon tube together with the discharge head 6 are assembled to the bottle as indicated in Fig. 1, the space *a* above the level of the aerated liquid *b* stored in the bottle can be directly connected via the aperture or apertures 4 and gas release valve 5 in the carrier, with the valve 7 of the discharge head.

In the construction shown in Fig. 1, the carrier 3 comprises a detachable extension 3a that is cast or otherwise secured on the siphon tube 1, and forms an internally threaded socket adapted for engagement with the externally threaded lower end of the carrier, an annular packing 8 being arranged in the socket-like detachable extension 3a so as to form a gas tight joint between the carrier and its extension when these elements are assembled, as indicated.

The upper part of the carrier 3 is adapted to form a socket 9, the exterior of which is flanged at 9a, and dimensioned to fit into the body of the discharge head 6 and form therein an annular groove for the usual gasket or neck washer 10 that forms a gas tight joint between the lip 2a of the bottle and the discharge head 6, and also the support for the carrier 3.

A plurality of inclined apertures or passages 4 are formed in the annular wall of the carrier 3, the lower ends of which passages terminate in external openings 4a, while their upper ends 4b terminate in an annular connecting groove 9b formed in the bottom of the socket 9 in which socket is arranged the non-return gas release valve 5. Such gas release valve consists of an annular washer of India-rubber or other suitable elastic material that is adapted to lie flat on the bottom of the socket 9 so as to normally seal the connecting groove 9b therein. The valve 5 so formed is controlled by a flat annular plate 5a furnished with internal radial fingers 5b (see Fig. 2) that is superposed upon the elastic valve 5, which latter, together with its controlling spring is adjustably secured in the socket 9 by an externally threaded ring 11.

adapted to engage the counterpart internally threaded wall 9c of the socket.

The ring 11 is slotted as indicated at 11b for engagement with a box spanner or other instrument for screwing and unscrewing the same.

The bore of the carrier 3 is formed at its upper end with an internally coned seating 12a for a glass or other suitable ball valve 12, which is normally held against its seating 12a by a spring 13 carried on the upper end of the siphon tube 1 so as to close the bore of the carrier and its siphon tube 1.

The discharge head 6 is furnished as usual with a spout 14 and an internal waterway 15 which is surrounded by a downwardly extending annular flange 15a that forms the seating for the valve 7 of the discharge head, such valve being carried as usual by a spring controlled spindle 1a through which it is connected with the operating lever 16 of the discharge head; the lower end or skirt of the discharge head 6 is internally threaded as indicated at 6a for engagement with the counterpart external thread 17a of the neck ring 17 by which the discharge head is secured upon the neck of the bottle 2 in known manner so as to compress the gasket or neck washer 10 against the lip of the bottle and form a gas tight joint.

The valve 7 in the discharge head opens downward from its seating by manipulation of the operating lever 16 in the ordinary manner. As the valve 7 opens the gas pressure in the interior of the discharge head 6 drops, and if the resistance of the gas release valve 5 and its controlling spring is less than the gas pressure in the space a above the liquid level in the bottle 2, the release valve 5 is momentarily opened by the unbalanced gas pressure, so that excess gas escapes from the space a in the bottle past the gas release valve 5 and the valve 7, and as the opening of the latter valve continues its extension 1b bears against and opens the liquid release valve 12 against the resistance of its spring 13 and the internal pressure in the siphon tube, so that the aerated liquid rises through the tube 1 past the open release valve 12 and follows the previously vented gas past the valve 7 to the spout 14 from which it is quietly delivered in a state of maximum aeration.

On releasing the valve operating lever 16 of the discharge head the valve 7 in the latter closes, so releasing the valve 12 in the carrier, which is simultaneously closed by its controlling spring, while the gas pressure below the closed valve 7 of the discharge head is restored by the passage of gas through the gas release valve 5 from the interior space a of the bottle or like container.

In the construction shown at Fig. 3 a plurality of apertures 4 is formed in the wall of the tubular carrier 3, the inner ends of such apertures terminating in a connecting groove 4x formed in the inner surface of the carrier, in the bore of which the gas release valve 5 is mounted.

The gas release valve 5 is formed by a sleeve of India-rubber or other suitable material, the lower end 5x is thickened and externally serrated and cemented or otherwise secured gas tight in counterpart serrations in the bore of the carrier, below the groove 4x therein, as indicated at 5y, while the elastic valve 5 formed by the upper part of the sleeve is free, and normally seats gas tight against the concentric surface 5z above the groove 4x in the bore of the carrier.

The thickened lower end 5x of the sleeve is

internally coned to form the seating 12a for the spring controlled ball valve 12, that normally closes the bore of the carrier 3, and siphon tube, under the influence of its controlling spring 13 that is mounted in the detachable extension 3a of the carrier. The extension 3a is cast or otherwise secured on the upper end of the siphon tube 1 and is externally threaded to receive the counterpart internally threaded lower end of the carrier 3; the upper end of the carrier is outwardly flared and terminates in an external flange 3x by which it is suspended from the gasket or neck-washer 10, that is clamped between the lip 2a of the bottle and the discharge head 6, when this latter together with the carrier 3 are assembled to the bottle 2 as previously described.

The valve 7 of the discharge head is furnished with an extension 1b and is enclosed by the flared upper end of the carrier 3 and normally seats on the annular elastic seating piece 15a to seal the waterway 15 through the discharge head, while the flange 3x of the carrier is clamped gas tight between the seating piece 15a and the gasket or neck washer 10.

In the modification shown, in Figs. 4 and 5 a single inwardly flared aperture 4 is formed in the wall of the tubular carrier 3, and is normally closed by the gas release valve 5, consisting of a ball, under the influence of a horizontally disposed spring 20 loosely mounted in the groove 4x in the bore of the carrier, in which groove terminates the flared inner end of the aperture 4.

In this construction the carrier 3 is formed in one piece, its lower end being secured about the top of the siphon tube 1, and is outwardly flared towards its upper end, which terminates in an external flange 3x, by which the carrier is suspended in the bottle or container, as described with reference to Fig. 2. The valve 7 of the discharge head is enclosed by the upper end of the carrier, so that when such valve is opened it bears against and operates the valve 12 mounted in the carrier and controlled by the spring 13 arranged in the lower end thereof.

As the valve 7 opens, the pressure of excess gas trapped in the space a above the liquid in the bottle automatically opens the gas release 5, through which excess gas is vented, and escapes past the valve 7, the progressive movement of which then opens the valve 12, so allowing the aerated liquid to rise through the tube 1 and flow to the outlet of the discharge head, as previously described.

In this construction, the valve 12 is furnished with a tubular stem 21 provided with lateral openings 22, which stem works in a guide 23 in which the seating 12a is arranged for the valve 12. The guide 23 is secured in a parallel section 3k of the bore of the carrier 3 below the groove 4x therein, while the valve 12 is normally closed by its spring 13.

The upper end of the tubular stem 21 projects beyond the guide adjacent to the lower end of the valve 7 of the discharge head.

As the valve 7 is opened pressure of excess gas trapped in the space a within the bottle automatically opens the gas release valve 5, so venting excess gas in advance of the aerated liquid which rises through the tube 1 and the openings 22 in the tubular stem 21 of the valve 12 as the latter is opened by the progressive operation of the valve 7 in the discharge head.

As the valve 7 closes the valve 12 simultaneously closes under the influence of its controlling

spring 13, so preventing further liquid rising in the siphon tube until the next operation.

I claim:—

5. In a siphon bottle or similar container for storing and dispensing aerated liquid, the combination with a discharge head having an outlet valve and an internal siphon tube connected therewith of an automatic gas release valve adapted to permit the escape into the discharge head of excess gas collected above the liquid stored in the container and means to effect the escape of the gas from the discharge head in advance of the delivery of liquid through the discharge head when the valve in the latter is operated, the discharge head serving to retain the gas therein until said outlet valve is operated.
10. A siphon bottle for storing and dispensing aerated liquid comprising a discharge head having an outlet valve and an internal siphon tube suspended in the bottle and connected with the valve in the discharge head by a siphon tube carrier having apertures formed therein so as to connect the space above the aerated liquid stored in the bottle with the valve in the discharge head, and a gas release valve mounted in said carrier so as to normally close the apertures therein and allow excess gas collected above the liquid level in the bottle to escape into the discharge head and means to effect the escape of the gas from the discharge head in advance of the delivery of the aerated liquid on operation of the valve in said discharge head, the discharge head serving to retain the gas therein until said outlet valve is operated.
15. A siphon bottle for storing and dispensing aerated liquid comprising a discharge head having an outlet valve and an internal siphon tube suspended in the bottle and connected with the valve in the discharge head by a siphon tube carrier having apertures formed therein so as to connect the space above the aerated liquid stored in the bottle with the valve in the discharge head, and a gas release valve mounted in said carrier so as to normally close the apertures therein and allow excess gas collected above the liquid level in the bottle to escape into the discharge head and means to effect the escape of the gas from the discharge head in advance of the delivery of the aerated liquid on operation of the valve in said discharge head, the discharge head serving to retain the gas therein until said outlet valve is operated.
20. A siphon bottle for storing and dispensing aerated liquid according to claim 4 wherein the carrier for the siphon tube is furnished at one end with a detachable extension in which said tube is secured, and terminates at the other end in an externally flanged socket adapted to fit into the body of the discharge head and form therewith an internal annular groove for the neck washer or gasket, passages formed in the wall of said carrier terminating in external openings at one end, and at the other end within the socket of the carrier, a non-return gas release valve comprising an annular disc mounted in the bottom of such socket so as to close the openings therein, and controlled by an annular spring furnished with internal radial fingers, said valve disc and spring being secured in such socket by an adjustable screw ring, the bore of the tubular carrier having an internally coned seating for a spring controlled valve mounted therein so as to be operated by the valve in the discharge head when the latter is opened, substantially as hereinbefore described.
25. A siphon bottle for storing and dispensing aerated liquid according to claim 4 wherein the carrier for the siphon tube is furnished at one end with a detachable extension in which said tube is secured, and terminates at the other end in an externally flanged socket adapted to fit into the body of the discharge head and form therewith an internal annular groove for the neck washer or gasket, passages formed in the wall of said carrier terminating in external openings at one end, and at the other end within the socket of the carrier, a non-return gas release valve comprising an annular disc mounted in the bottom of such socket so as to close the openings therein, and controlled by an annular spring furnished with internal radial fingers, said valve disc and spring being secured in such socket by an adjustable screw ring, the bore of the tubular carrier having an internally coned seating for a spring controlled valve mounted therein so as to be operated by the valve in the discharge head when the latter is opened, substantially as hereinbefore described.
30. A siphon bottle for storing and dispensing aerated liquid according to claim 4 wherein the carrier for the siphon tube is furnished at one end with a detachable extension in which said tube is secured, and terminates at the other end in an externally flanged socket adapted to fit into the body of the discharge head and form therewith an internal annular groove for the neck washer or gasket, passages formed in the wall of said carrier terminating in external openings at one end, and at the other end within the socket of the carrier, a non-return gas release valve comprising an annular disc mounted in the bottom of such socket so as to close the openings therein, and controlled by an annular spring furnished with internal radial fingers, said valve disc and spring being secured in such socket by an adjustable screw ring, the bore of the tubular carrier having an internally coned seating for a spring controlled valve mounted therein so as to be operated by the valve in the discharge head when the latter is opened, substantially as hereinbefore described.
35. A siphon bottle for storing and dispensing aerated liquid comprising a discharge head having an outlet valve and an internal siphon tube suspended in the bottle and connected with the valve in the discharge head by an apertured tubular carrier furnished with a flexible non-return automatic gas release valve arranged in combination with the apertures in the carrier so as to permit the escape of excess gas from the space above the level of the liquid stored in the bottle into the discharge head and means to effect the escape of the gas from the discharge head in advance of the delivery of the aerated liquid that rises through said siphon tube on each operation of the valve in the discharge head, the discharge head serving to retain the gas therein until said outlet is operated.
40. A siphon bottle for storing and dispensing aerated liquid comprising a discharge head having a downwardly opening outlet valve, an internal siphon tube suspended within the bottle and connected with the valve in the discharge head, such tube being normally closed by a spring controlled non-return valve adapted to close on a seating in the bore of said tube and arranged so as to be opened by the valve in the discharge head, apertures in said tube connecting the space above the liquid level in the bottle with the valve in the discharge head, and an automatic gas release valve arranged in said tube so as to normally seal the apertures therein, and permit excess gas to escape in advance of the delivery of the aerated water on each operation of the discharge head.
45. A siphon bottle for storing and dispensing aerated liquid according to claim 4 wherein the carrier for the siphon tube is furnished at one end with a detachable extension in which said tube is secured, and terminates at the other end in an externally flanged socket adapted to fit into the body of the discharge head and form therewith an internal annular groove for the neck washer or gasket, passages formed in the wall of said carrier terminating in external openings at one end, and at the other end within the socket of the carrier, a non-return gas release valve comprising an annular disc mounted in the bottom of such socket so as to close the openings therein, and controlled by an annular spring furnished with internal radial fingers, said valve disc and spring being secured in such socket by an adjustable screw ring, the bore of the tubular carrier having an internally coned seating for a spring controlled valve mounted therein so as to be operated by the valve in the discharge head when the latter is opened, substantially as hereinbefore described.
50. A siphon bottle for storing and dispensing aerated liquid comprising a discharge head having an outlet valve, and an internal siphon tube suspended within the bottle and connected with the valve in the discharge head by an apertured

EDWARD JOSEPH PAUL EUGSTER.
